UNITED STATES PATENT OFFICE

WILFRID J. ROY, OF EAST ORANGE, NEW JERSEY, ASSIGNOR TO GEMEX COMPANY, OF NEWARK, NEW JERSEY, A CORPORATION OF NEW JERSEY

WATCH-BRACELET-CONNECTING DEVICE

Application filed April 2, 1930. Serial No. 440,949.

This invention relates to a device for connecting a bracelet or chain to a wrist watch, commonly called an "end hook", and has for its object to provide means by which the device may be detachably secured to the bracelet.

A further object of the invention is to provide a construction which may be removably attached to the watch and removably attached 10 to a bracelet by providing a removable part for obstructing the entering opening of a portion which receives the bracelet.

With these and other objects and advantageous features in view, the invention consists of a novel arrangement of parts more fully disclosed in the detailed description following, in conjunction with the accompanying drawings, and more particularly set forth in the appended claims.

20 In the drawings:

Fig. 1 is a top plan view of the device with a link bracelet or chain attached thereto;

Fig. 2 is a bottom view showing the removable pin in section;

25 Fig. 3 is a perspective view of the end link of the bracelet;

Fig. 4 is a section of the device, and a partial section of the end link of the bracelet secured thereto;

30 Fig. 5 is a sectional view of the connecting device or end hook with the pin removed;

Fig. 6 is a perspective view of the yoke which provides the eyes at either side of the device;

35 Fig. 7 is a perspective view of the removable pin;

Fig. 8 is a perspective view of the device with the yoke carrying the eyes removed therefrom;

40 Fig. 9 is a perspective view of a modified form of construction showing the eyes as formed integral with the device;

Fig. 10 is a perspective view of the structure of Figure 9 looking at the opposite side

45 thereof;

Fig. 11 is a section on the line 11—11 of Figure 9.

It is found in the use of bracelets of the type for securing a watch to the wrist of 50 the wearer of advantage to provide a con-

nnecting device for the end of the bracelet which may readily be attached to the lugs of a wrist watch; and as the lugs on different wrist watches are of varying distances apart, it is found desirable to provide a construction in which connecting devices of various widths may be interchanged with one another on the end of the bracelet so as to accommodate the bracelet to different watches; and in order to accomplish this result, I have provided a connecting device having a body portion with an eye secured to one end to receive the removable pin extending between the lugs of the watch, and have formed the other end of the body portion into a hook with a removable part blocking the entrance to the hook so that when attached to the bracelet with the removable part in operating position, it is prevented from being disconnected therefrom; and the following is a detailed description of the preferred means by which these advantageous results may be accomplished.

With reference to the drawings, 15 designates the links of the bracelet chain which are suitably hingedly connected together by band links 16, and to an end link 15 I have secured the connecting device 17 which consists of a body portion 18 provided with an eye 19 to receive a pin, not shown, for connecting the same between the lugs of a wrist watch. A hook 20 is provided at the opposite end of the body to receive the cross bar 21 of the link 15. Eyes 22 are provided on the body 18 by means of a yoke 23 extending across the back of the body and positioning the eyes opposite each other to receive the tubular pin 24 for obstructing the entrance 25 to the hook 20.

The tubular pin 24 is provided with trunnions 26 extending from each end thereof, each having shoulders 27 to engage the in-turned portions 28 of the pin to prevent removal therefrom by means of a spring 29 forcing the same outwardly, as illustrated in Figure 2, thereby causing the trunnions 26 to be resiliently forced into the openings 30 in the eyes 22 and so positioning the pin 24 as to obstruct the opening 25 and prevent

removal of the cross bar 21 of the link 15 from the hook.

The yoke 23 is held in position by solder assisted by lugs 31, shown in Figure 8, which 5 support this yoke from against a strain longitudinally of the body 18. In some instances, the eyes 22 are integral with the body 18 and folded down into desired position, as shown in Figures 9 and 10. The position, 10 however, is such as to receive the pin as above described in a position to obstruct the opening and function as before.

While I have described certain construction forms which embody the principles of my 15 invention, it is obvious that other desired changes in arrangement may be made within the spirit and the scope of the invention as defined in the appended claims.

I claim:

1. A device for securing a bracelet to a 20 watch comprising a body member provided with a tubular portion at one end to be attached to the crossbar of a wrist watch, and means at the other end for detachably securing the body member to a bracelet chain, said last mentioned means comprising a portion having an opening to receive a part of the bracelet and a member functionally independent of said tubular portion and detach- 25 ably mounted on said body member across the mouth of said opening only, for obstructing the entrance thereto.

2. A device for securing a bracelet to a 30 watch comprising a body member provided with a tubular portion at one end to be attached to the crossbar of a wrist watch, a hook at the opposite end of said body member to engage a bracelet link, and removable means 35 functioning independently and separately from said tubular portion mounted on said body member across the mouth of said hook only, for obstructing the entering opening of said hook.

3. In a device for securing a bracelet to a 40 watch, a body member provided with means at one end to be attached to the lug of a wrist watch, a hook at the opposite end of said body member functioning independently and separately from said means to engage a bracelet link, and a pin mounted on said body member for closing the opening to said hook, and means for removing mounting said pin in position to obstruct the opening to said hook.

4. In a device for securing a bracelet to a 50 watch, a body member provided with means at one end to be attached to the lug of a wrist watch, a hook at the opposite end of said body member to engage a bracelet link, eyes provided at the sides of said body member, 55 and means removably secured in said eyes to close the opening to said hook.

5. In a device for securing a bracelet to a 60 watch, a body member provided with means at one end to be attached to the lug of a wrist 65 watch, a hook at the opposite end of said

body member to engage a bracelet link, eyes provided at the sides of said body member, and a pin having resilient portions removably secured in said eyes to close the opening to said hook.

6. In a device for securing a bracelet to a 70 watch, a body member provided with means at one end to be attached to the lug of a wrist watch, a hook at the opposite end of said body member to engage a bracelet link, eyes provided at the sides of said body member, a tubular pin extending between said eyes, trunnions in the ends of said pin extending into the openings in said eyes, and a spring in 75 said pin resiliently holding said trunnions in position but permitting them to be forced inwardly for removing the pin.

In testimony whereof I affix my signature.

WILFRID J. ROY.
